FIG. 1

FIG. 2

FIG. 4

FIG. 3

FIG. 5

FIG. 6

FIG. 1 is a top plan view of a surgical drape showing my new design;

FIG. 2 is a bottom plan view thereof;

FIG. 3 is a left side elevation view thereof on an enlarged scale, which is a mirror image of the right side elevation thereof;

FIG. 4 is an end view as seen from the top of FIG. 1, on an enlarged scale;

FIG. 5 is an end view as seen from the bottom of FIG. 1, on an enlarged scale; and

FIG. 6 is a top perspective thereof.

The characteristic feature of the design resides in the rectangular form folded on three sides, two opposing sides and a third side. The third side is folded substantially larger than the other two sides to form a pocket. A continuous stitch is run on the folds of the two opposing sides and is perpendicular to the stitched open end of the pocket.

I claim:

The ornamental design for a surgical drape, as shown and described.
